UNITED STATES PATENT OFFICE.

AUGUSTUS M. SOSA, OF CINCINNATI, OHIO, ASSIGNOR TO THE AMERICAN TOOL WORKS COMPANY, OF CINCINNATI, OHIO, A CORPORATION OF OHIO.

DRILLING MACHINERY.

1,338,752.

Specification of Letters Patent.

Patented May 4, 1920.

Application filed September 10, 1917. Serial No. 190,654.

To all whom it may concern:

Be it known that I, AUGUSTUS M. Sosa, a citizen of the United States, residing at Cincinnati, in the county of Hamilton and State of Ohio, have invented certain new and useful Improvements in Drilling Machinery, of which the following is a specification.

My invention relates to drilling machinery, and I have exemplified the same as embodied in a radial drilling machine.

In machinery of this character it is desirable to adjust the point of the drill accurately to the point on the work at which the point of the drill is to enter the work. This is accomplished by lateral and axial adjustments of the drill-spindle. The initial lateral movements of the drill-spindle may be rapid for proximate positioning of the drill-spindle, but, in machines as heretofore usually constructed, the movements of the drill-spindle for final adjustments are necessarily slow and finely divided both laterally and axially of the drill-spindle, and the adjustments difficult and uncertain.

It is the object of my invention to provide means whereby the facility and accuracy of adjustment of the drill-spindle with relation to the work is enhanced.

It is the object of my invention, further, to provide means for laterally adjusting the drill-spindle comprising a manual operating part at each side of the drill-spindle, one of said manual operating parts arranged for quick traverse adjustments of the drill-spindle, and the other of said manual operating parts arranged for fine lateral adjustments of the drill-spindle.

It is the object of my invention, further, to provide means for laterally and axially adjusting the drill-spindle by manual operating parts respectively at the respective sides of the drill-spindle for imparting to the point of the drill a movement in a direction which is the resultant of the simultaneous adjustment of the drill-spindle in lateral and axial directions.

It is the object of my invention, further, to provide means whereby the fast lateral movements of the drill-spindle may be accomplished by a manual operating part at one side of the drill-spindle or operator's position, and the axial adjustments of the

drill-spindle may be accomplished by means of a manual operating part at the same side 55 of the drill-spindle, the two manual operating parts mentioned being independently operable, so that said two manual operating parts may be manipulated separately by one hand of the operator, and to 60 provide a manual operating part at the other side of the drill-spindle or operator's position, operable by the other hand of the operator, so that the final accurate adjustments of the drill-spindle, both axially and 65 laterally, may be accomplished by simultaneous use of both hands of the operator, by manipulation of manual operating parts at the respective sides of the drill-spindle or operator's position, in order to move the 70 point of the drill simultaneously in both directions toward the point on the work at which the point of the drill is to enter.

It is a further object of my invention to mount the devices mentioned on a radially 75 adjustable arm simultaneously movable with said manual operating parts for conveniently and effectively obtaining the required adjustments; and, further to so arrange the manual manipulating parts that the same 80 may be manipulated by both hands of the operator so positioned that he is able to simultaneously observe the effect of the adjustments being made in order to have complete control of the same and for effecting 85 the same speedily.

The invention will be further readily understood from the following description and claims, and from the drawings, in which latter:

Figure 1 is a front elevation of a drilling machine, embodying my invention.

Fig. 2 is a side elevation of the tool-slide, partly broken away, and partly in section taken on the line 2—2 of Fig. 1.

Fig. 3 is a horizontal section of the tool-slide, taken in the plane of the line 3—3 of Fig. 2.

Fig. 4 is a detail section of the feeding mechanism for the drill-spindle, taken on 100 the line 4—4 of Fig. 3.

Fig. 5 is a front elevation of my improved device, with parts partly broken away, and partly in axial section in the plane of the line 5—5 of Fig. 9, the feeding clutch being 105 shown released.

Fig. 6 is a horizontal cross-section taken in the plane of the line 6—6 of Fig. 5.

Fig. 7 is an axial section of the speed changing device for the feeding means, 5 taken in the plane of the line 7—7 of Fig. 5.

Fig. 8 is a horizontal sectional detail, taken on the line 8—8 of Fig. 4.

Fig. 9 is a horizontal section of the tool-slide and its support, taken in the plane of 10 the line 9—9 of Fig. 2.

Fig. 10 is a vertical section taken on the line 10—10 of Fig. 9; and,

Fig. 11 is an enlarged detail of the clamping means between the feeding worm-wheel 15 and the face-plate, taken on the line 3—3 of Fig. 2.

The drilling machine, which is exemplified as a radial drilling machine, may comprise a usual base 11 from which a post 12 20 extends upwardly, an upright column 13 being rotatable about the post in usual manner and arranged to be clamped in adjusted positions by means of a clamp 14. A drill-arm 15 extends from the column, being 25 adjustable up and down on the column by being provided with a bearing 16 about the column, a screw-rod 17 having threaded connection with a usual nut in the bearing of the drill-arm and arranged to be rotated 30 in reverse directions from a shaft 18 by suitable gearing in the housing 19 at the top of the column controlled by an operating rod 20 extending lengthwise of the column and provided with a suitable handle 21, in 35 any usual or ordinary manner.

The rotatable column is rotatable about the post for readily positioning the drill-arm, the clamp 14 being arranged to clamp the rotatable column to the base upon 40 proper adjustment being attained.

The base comprises a table 22 on which the work, exemplified by a casting 25, is arranged to be laid or suitably secured.

A tool-slide 26 supports a drill-spindle 45 27 and mechanism for rotating and feeding the same, and is adjustable lengthwise on the drill-arm by a guideway 29 thereon co-acting with a guide 28 on the drill-arm. The drill-spindle is arranged to receive a 50 suitable drill 30, and has the same fixed thereto in usual manner, the drill having an entering point 31 in the axial center thereof arranged to enter the work.

The drill-spindle is arranged to be rotated in suitable manner, exemplified as accomplished by a shaft 35 extending lengthwise of the drill-arm and operated in suitable or usual manner by an upright shaft 36 receiving motion in usual manner by gearing in the housing 19, said gearing operated by the shaft 18. The shaft 18 is operated at various speeds by a drive-shaft 37. The driving connection between the shafts 36 and 35 is had by means of gearing in a gear 60 cover 38. (See Fig. 1.)

Bevel-gears 41, 42, are arranged to be selectively operatively connected with the shaft 35, as by means of usual clutches selectively actuated by an operating arm 43, for rotating a bevel-gear 44, in mesh at its opposite sides with the bevel-gears 41 and 42, in opposite directions. The bevel-gear 44 is fast with a gear 45 which meshes with a gear 46 on a shaft 47 journaled in a bearing 48 on the tool-slide. The shaft 47 has 70 a gear 49 fast thereon which meshes with a gear 50 having spline-connection 51 with the drill-spindle for rotating the same.

The drill-spindle is arranged to be moved axially by feeding mechanism exemplified as comprising a rack 55 on a sleeve 56 about the drill-spindle, the sleeve being axially movable in a bearing 57 on the tool slide and prevented from turning by a key 58 thereon movable lengthwise in a groove 59 of 80 said bearing. End-thrust bearings 61, 62, cause axial movement of the drill-spindle with the sleeve. A pinion 63 meshes with the rack and is on a shaft 64 fast with a face-plate 65 and a bushing 66 thereon, in which the shaft is received. A worm-wheel 67 has a bearing 68 about the bushing and is in turn rotatable in a bearing 69 in the tool-slide.

The worm-wheel and face-plate have an 95 annular bearing 70 between them. The worm-wheel and face-plate are arranged to be clamped together by a clamp 71, when it is desired to cause feeding movement of the drill-spindle by means of the worm-wheel. (See Figs. 3 and 11.) If it is desired to impart a quick axial adjustment to the drill-spindle, the clamp 71 is released, the face-plate being provided with handles 72 positioned at the front of the tool-slide, 100 for turning the same.

Means are also provided for feeding the tool-spindle axially selectively either by means of power or manual operation, effected by rotation of the worm-wheel, exemplified as accomplished by means of a worm 75 in mesh with the worm-wheel. The worm is fixed to a shaft 76 journaled in a bearing 77 on the tool-slide and having a manual operating part, shown as a hand-wheel 78 fast thereon and having a handle 79 thereon. An upright shaft 81 is arranged to be driven at selective speeds through suitable nests of gears, indicated at 80 and 82, and operated by means of a gear 110 83 in mesh with a gear 84 on the drill-spindle, rotating with the gear 50.

Exemplifying the nests of gears 80, 82, and the means for transmitting selective speeds to the upright shaft 81 thereby, the 115 nest of gears 80 is exemplified as consisting of gears relatively loosely rotating about a bushing 131 journaled in bearings 132 of the slide-frame. (See Figs. 5 and 7). The gear 83 is fixed to the bushing, the gears of 120 130

the nest of gears 80 being selectively connected with the bushing by means of a key 133, arranged to be selectively received in slots 134, one of which is in each of said gears, the key passing through a slot 135 extending lengthwise of the bushing. The key is pivoted at 136 to an axially movable rod 137 and is urged into the slots of the gears by means of a spring 138 secured to 10 said rod.

The rod is provided with an annular rack 141 with which a pinion 142 meshes, the pinion being on a shaft 143 journaled in a bearing 144 in the slide-frame and having 15 a handle 145 thereon for rotating the same, and thereby moving the rack axially. Rings 146 are located about the bushing between proximate gears to cause disengagement of the key from a gear when the key is moved 20 axially and to prevent engagement of the key with more than one gear at a time.

The selective speeds are indicated on a gage 148 rotating with the shaft 143, the markings on the gage being arranged to 25 register with a pointer 149 fixed to the slide-frame.

The gears of the nest of gears 82 are fixed to a shaft 151 journaled in bearings 152 in the slide-frame. A gear 153 is fixed to the 30 shaft and meshes with a gear 154 fixed to the shaft 81.

The shaft 81 is journaled in a bearing 85 and is received in a bore 86 of the worm. A clutch 87 is located between the shaft and 35 worm, exemplified as a tooth-clutch, the teeth of which are respectively on the worm and on a collar 88 having spline-connection 89 with the shaft 81. The collar is arranged to be moved axially on the shaft for engaging 40 or disengaging the clutch by means of a fork 91, the tines of which are received in an annular groove 92 in said collar, the fork being on a rocker-rod 93 journaled in a bearing 94 of the tool-slide and having an 45 operating arm 95 thereon.

In order to adjust the tool-slide laterally on the drill-arm, I provide the drill-arm with a rack 101 extending lengthwise thereof, engaged by a pinion 102 on a shaft 103 50 journaled in a bearing 104 on the tool-slide and meshed by a pinion 105 fast on a shaft 106 journaled in bearings 107 on the tool-slide. A worm-wheel 108 is fast on said shaft. A worm 109 meshes with the worm-wheel and is arranged to be rotated in opposite directions for adjusting the tool-slide laterally in reverse directions on the drill-arm. It may rotate in an oil-cup 100. The 55 worm 109 is on a cross-shaft 110, which extends transversely of the tool-slide and has a manual manipulating operating part at each side of said tool-slide, one of these operating parts being for the purpose of quick or extended lateral movement of the 60 tool-slide on the drill-arm, and the other of

said parts being for the purpose of slight and accurate lateral adjustments of said tool-slide.

The first of these adjusting parts is exemplified at the right-hand end of said 70 cross-shaft as a hand-wheel 111, having a handle 112 thereon to form a crank-wheel, whereby the operator, whose position is in front of the tool-spindle, as at *a*, may operate the hand-wheel 111 with his right 75 hand for quick lateral adjustments. The other of these operating parts is exemplified as a hand-wheel 115 at the left-hand end of said cross-shaft, whereby the operator may accomplish lateral adjustment of the tool- 80 spindle by means of his left hand, this hand-wheel being preferably without a handle so that the hand of the operator may slide about the same or grasp the same at any desired point in its circumference. 85

The cross-shaft is exemplified as journaled in bearings 116, 117, on the tool-slide. The bearing 117 is instanced as comprising a bushing 118 secured in the tool-slide, and having end-thrust bearings 119, 120, between 90 said bushing and a shoulder 121 on said shaft at one end of said bushing and the hub of the hand-wheel 111 at the other end of said bushing. Said hub has spline-connection 122 with said shaft, an adjusting nut 123 threaded to the end of said shaft adjusting said bearings.

The end-thrust bearings, exemplified as ball-bearings, afford ease of rotation of the shaft and prevent endwise play of the shaft, 100 causing transference of all rotary motion of the shaft into cross-adjustment of the spindle.

In operation, if the operator desires to adjust the point 31 of the drill into co-operative 105 relation with a point, exemplified as the point of intersection of the lines of the cross-mark *b* in Fig. 6, said last-named point being usually made by a prick-punch on the work, and assuming that the tool-slide is 110 distanced laterally to considerable extent from said work, the operator will employ his right hand for rotating the hand-wheel 111 by means of the handle 112 thereon, whereby he obtains a rapid lateral transverse movement of the tool-slide on the drill-arm for proximate relation between the drill and the point of application on the work. Having thus obtained approximate position of the tool-slide, the operator, who is at the 115 operator's position *a*, operates the hand-wheel 78 with his right hand for causing descent of the drill, and the operator simultaneously with his left hand operates the hand-wheel 115 for causing the finer and accurate lateral adjustments of the tool-slide. 120

By manipulating both these hand-wheels at the same time, the point of the drill is given an inclined downward movement, ex- 125 130

emplified by the dotted line *c* in Fig. 5, toward the point of application on the work, the plane of which is instanced by the dotted line *d* in Figs. 1 and 5, and the operator, whose position is immediately in front of the drill-spindle when so manipulating the manual controls for the drill-spindle, has the relation of the drill-point and the point of its desired application to the work immediately before his eyes, so that he can closely observe the effect of his relative manual manipulations by his respective hands of the hand-wheels controlling respectively the axial movement and the cross adjustment of the drill, and can accurately accelerate, retard or stop either or both of said movements for obtaining the desired result.

The adjustment of the tool with relation to the work is thus quickly and accurately accomplished, and if it is desired, during said adjustment, to shift the position of the drill-arm, this is readily accomplished by exerting manual force upon the hand-wheels while rotating the same and in the desired direction for shifting the radial position of the drill-arm.

Having thus fully described my invention, what I claim as new and desire to secure by Letters Patent, is:

30 1. In a drilling machine, the combination of a work-support, a tool-slide arranged for having a drilling tool secured thereon above said work-support, and means for laterally adjusting said tool-slide toward the right or left for causing the point of said drilling tool to register with a given point on the work on said work-support, said means including a manual operating part at the right of said tool-slide and a manual operating part at the left of said tool-slide for effecting said adjustments.

2. In a drilling machine, the combination of a drill-arm, guides extending lengthwise thereof, a tool-slide, a drill-spindle thereon arranged for receiving a drill, means for laterally adjusting said tool-slide along said guides toward the right or left for work-position, said means including a manual rotatable operating part at the right of said tool-slide and a manual rotatable operating part at the left of said tool-slide for effecting said lateral adjustments of said tool-slide, and means for adjusting said drill-spindle up and down comprising a manual rotatable operating part at the right of said tool-slide, and constructed and arranged whereby there is freedom of view of said drill between said last two named manual operating parts in a line of vision projected toward the point of said drill in a plane perpendicular to the vertical plane parallel with said guides in which said guides are located.

3. In a drilling machine, the combination of a tool-slide, a drill-spindle thereon,

a work-support under said drill-spindle, means for laterally adjusting said tool-slide toward the right or left for work-position, and means for adjusting said drill-spindle up and down, said first-named means and said second-named means each including a manual rotatable operating part on said tool-slide to the right of said drill-spindle arranged for independent operation and provided with a handle extending substantially parallel with its axis of rotation for continuous adjustments thereby, and said first-named means further including a manual operating part of wheel form to the left of said drill-spindle arranged for co-operation with said manual operating part of said second-named means for interrupted adjustments of said drill-spindle to adjust said drill-spindle to cause the point of the drill on said drill-spindle to move laterally and downwardly to coincide with a given point on the work on said work-support.

4. In a radial drilling machine, the combination of a column, a radial drill-arm thereon adjustable to radial positions, a tool-slide, a drill-spindle thereon, a work-support under said drill-spindle, means for laterally adjusting said tool-slide to the right or left on said drill-arm for work-position, and means for adjusting said drill-spindle up and down, said first-named means and said second-named means each including a manual rotatable operating part on said tool-slide to the right of said drill-spindle arranged for independent operation, each of said manual rotatable operating parts provided with a handle extending substantially parallel with its axis of rotation for continuous adjustments thereby of said drill-spindle, said first-named means further including a manual rotatable operating part of wheel form to the left of said drill-spindle arranged for co-operation with said manual operating part of said second-named means for interrupted adjustments of said drill-spindle to cause the point of the drill on said drill-spindle to move laterally and downwardly to coincide with a given point on the work on said work-support, and said last-named two manual operating parts arranged by pressure thereon to shift said drill-arm to selective radial positions.

5. In a drilling machine, the combination of a drill-arm, a laterally adjustable slide thereon, a drill-spindle on said slide, a work-support under said drill-spindle manually controlled means for axially adjusting said drill-spindle comprising a manual operating part arranged on said slide on one side of said drill-spindle convenient to one hand of the operator of the machine, and manually controlled means for making adjustments of said slide comprising a manual operating part arranged on said slide at said last-named side of said drill-

- spindle convenient to said last-named hand of the operator of the machine, and said last-named manually controlled means comprising an additional manual operating 5 part for making adjustments of said slide arranged on said slide at the opposite side of said drill-spindle convenient to the other hand of the operator of the machine, said first-named manual operating part and 10 said last-named manual operating part located at opposite sides of said drill-spindle for simultaneous operation by both hands of the operator positioned in front of said drill-spindle.
- 15 6. In a drilling machine, the combination of a supporting arm, a tool-slide on said supporting arm, a work-support under said tool-slide, guides between said tool-slide and said supporting arm extending lengthwise 20 of said supporting arm, a drill-spindle journaled on said tool-slide, means for axially adjusting said drill-spindle on said tool-slide comprising a manual operating part at one side of said slide, a rack on said 25 supporting arm parallel with said guides, a pinion on said slide engaging said rack for lateral adjusting of said slide on said arm, an operating shaft on said slide parallel with said guides having driving connection 30 with said pinion, and a manual operating part at each end of said operating shaft for manually rotating said operating shaft from either end thereof, said last-named manual operating parts including a crank-wheel at 35 that side of said slide at which said first-named manual operating part is located for continuous traverse movements of said slide, and a plain hand-wheel at the opposite side of said slide arranged to be grasped by the 40 hand at various parts of its circumference for interrupted traverse adjustments of said slide in connection with simultaneous axial adjustments of said spindle, by operation of said plain hand-wheel and said 45 first-named manual operating part simultaneously by both hands of one operator, substantially as described.
7. In a drilling machine, the combination of a tool-slide, a support therefor, a laterally extending guide between said support and said tool-slide, a drill-spindle, a work-support under said drill-spindle, means for adjusting said drill-spindle up and down on said tool-slide, a rotatable manual adjusting part at each side of said tool-slide at the 50 respective sides of said drill-spindle for lateral adjustments of said tool-slide on said support by means of either of said rotatable manual adjusting parts, one of said 55 rotatable manual adjustable parts provided with a handle extending substantially parallel with its axis of rotation, and a rotatable manual adjusting part on said tool-slide at one side of said drill-spindle for adjusting 60 said drill-spindle up and down, and con- 65 structed and arranged whereby simultaneous adjustments are imported to said drill-spindle above said work-support simultaneously laterally and downwardly by means of one of said first-named rotatable 70 manual adjusting parts and said last-named rotatable manual adjusting part at opposite sides of said drill-spindle to cause the point of the drilling tool on said drill-spindle to coincide with a given point on the work on 75 said work-support to properly locate said drilling tool with relation to said work.
8. In a drilling machine, the combination of a work-support, a drill-arm, a guide extending lengthwise of said drill-arm, a tool-slide above said work-support, a drill-spindle thereon arranged for receiving a drilling tool, means for laterally adjusting said tool-slide along said guide toward the right or left for work position, said means including a manual rotatable operating part on said tool-slide at the right of said drill-spindle and a manual rotatable operating part on said tool-slide at the left of said 80 drill-spindle for effecting said lateral adjustments of said tool-slide, said first-named manual rotatable operating part provided with a handle extending substantially parallel with its axis of rotation, and means for adjusting said drill-spindle up and down on 85 said tool-slide comprising a manual rotatable operating part on said tool-slide at the right of said drill-spindle, and constructed and arranged whereby there is freedom of view of said drilling tool between said first-named manual rotatable operating part and said third-named manual rotatable operating part above said work-support in a line of vision projected toward the point of said 90 drilling-tool in a plane perpendicular to the 95 vertical plane parallel with said guide in which said guide is located.
9. In a drilling machine, the combination of a work-support, a tool-slide above said work-support, a laterally extending guide 100 for said tool-slide, a drill-spindle on said tool-slide, a hand-wheel on said tool-slide at each side of said drill-spindle for adjusting said tool-slide laterally on said guide, and a hand-wheel on said tool-slide at one 105 side of said drill-spindle for adjusting said drill-spindle up and down, and constructed and arranged for simultaneous manual rotations of one of said first-named hand-wheels and said last-named hand-wheel by 110 the respective hands of the operator at opposite sides of said drill-spindle for adjustment of the point of the drilling tool on said drill-spindle laterally and downwardly 115 to coincide with a given point on the work 120 on said work-support.
10. In a drilling machine, the combination of a work-support, a tool-slide above said work-support, a laterally extending guide for said tool-slide, a drill-spindle on 125

said tool-slide, a pair of hand-wheels on said tool-slide at one side of said drill-spindle respectively for lateral adjustment of said tool-slide on said guide and for up and 5 down adjustment of said drill-spindle, each of said hand-wheels provided with a handle extending substantially parallel to its axis of rotation, and a hand-wheel on said tool-slide at the other side of said drill-spindle 10 for lateral adjustment of said tool-slide on said guide arranged in conjunction with said first-named hand-wheel for up and down adjustment of said drill-spindle to adjust the point of the drilling tool on said 15 drill-spindle in an inclined path laterally and downwardly to coincide with a given point on the work on said work-support.

11. In a drilling machine, the combination of a work-support, a tool-slide above 20 said work-support, a laterally extending guide for said tool-slide, a drill-spindle on said tool-slide, a shaft on said tool-slide substantially parallel with said guide for

lateral adjustments of said tool-slide on 25 said guide, a hand-wheel at the end of said shaft at the left side of said drill-spindle when viewed looking toward the tool-slide from the operator's position in front of the tool-slide, a manual rotatable operating part provided with a handle extending substantially parallel with its axis of rotation 30 at the end of said shaft at the right side of said drill-spindle, and a manual rotatable operating part provided with a handle extending substantially parallel with its axis 35 of rotation on said tool-slide at the right side of said drill-spindle, substantially for the purposes described.

In testimony whereof, I have hereunto signed my name in the presence of two sub- 40 scribing witnesses.

AUGUSTUS M. SOSA.
